UNITED STATES PATENT OFFICE

FRANK X. RIPP, OF MADISON, WISCONSIN

OPERATING MECHANISM FOR WINDOWS

Application filed March 31, 1932. Serial No. 602,337.

The subject of this invention is an operating mechanism for casement windows and is in part a continuation of application Serial No. 528,684 filed April 8, 1931.

5 The purpose of this invention is to provide a compact, inexpensive and efficient operating mechanism for opening and closing casement windows that may be readily installed in a position where it may be actuated without disturbing the sash or screen. The mechanism has been so designed that it may be installed at the mill on the component parts of a knock-down window.

10 The improved operating mechanism is characterized by a simple and inexpensive bearing member, by a novel mounting of a laterally swinging screw shaft and by a provision for closing off a recess in the support to prevent the incursion of foreign 15 matter and insects.

A practical embodiment of the invention is illustrated in the accompanying drawing, in which:

Fig. 1 is a plan view of the operating 20 mechanism shown in opening position.

Fig. 2 is a similar view in closing position.

Fig. 3 is a longitudinal sectional view taken on the line 3—3 of Fig. 2.

Fig. 4 is a similar view of the sleeve and 25 screw shaft.

Fig. 5 is a sectional view on the line 5—5 of Fig. 2 showing the position of the shutter for movement to the left.

Fig. 6 is a sectional view on the line 6—6 30 of Fig. 2 showing the shutter reversed for movement to the right.

There is shown a portion of a window frame consisting of the usual stiles 5, sill 6 and stool 7. A sash 8 is mounted 35 in the frame for combined sliding and swinging movement by means of arms 9 positioned in alignment at the top and bottom of the sash and each carrying a roller 10 riding in a channeled trackway 11 in the 40 frame.

45 The operating mechanism for opening and closing the sash comprises a lever 12 and a screw shaft 13. The lever is fulcrumed in a plate 14 secured to the sill and pivotally retained in a similar plate 15 secured to the

under side of the sash. The plate 15 and the lever are fitted into a recess 16 when the sash is closed. The lever is provided with an aperture 17 for receiving a removable pin 18 pivotally attaching the fork 19 on the 55 outer end of the screw shaft 13.

The mounting of the screw shaft is placed more or less centrally of the sill and is disposed in a recess 20 in a furring strip 21 that is inserted between the sill and the 60 stool 7. The mounting consists of a bed plate 22 secured by screws 23 and having a finger 24 on its rear end provided with an aperture 25 for receiving the pivot pin 26 of an elongated bearing member or barrel. 65

The bearing member consists of a flat bottom plate 27 and an arched top plate 28 having lugs 29 inserted through apertures in the bottom plate and then upset to provide a rigid assembly. The rear end 30 of the 70 bottom plate is offset and the front end 31 in angled so that the surfaces in engagement with the bed plate will be reduced to a minimum.

A sleeve 32 within the bearing member 75 has a collar 33 on its forward end provided internally with screw threads 34 to form a nut. The sleeve is inserted in the bearing member from the front until the collar 33 abuts the forward face of the bearing mem- 80 ber. When thus assembled the sleeve projects beyond the rear end of the bearing member and receives a slip collar 35 secured by a cross-pin 36 and held thereby against the rear face of the bearing member. A 85 crank 37 is provided with a slot 38 for engaging the cross-pin 36. The collars 33 and 35 preferably bear on the offsets of the bottom plate 27.

The screw shaft 13 is threaded into the 90 nut and when the sash is closed it is completely housed in the sleeve. A set screw 39 secured axially in the rear end of the screw shaft limits opening of the sash by engaging the threaded front collar 33. This 95 prevents the screw shaft from leaving the sleeve and also regulates the extent of opening of the sash. When the sash is closed the fork 19 is accommodated in the recess 16 in the 100 sash and in the recess 20 in the furring strip.

In order to close off the recess 20 and prevent the entry of foreign matter, a guard plate 40 extends across the recess and is preferably attached to the bed plate 22. The 5 guard plate is formed on an arc having as its center the pivot pin 26 of the laterally swinging bearing member. An elongated aperture 41 in the guard plate accommodates the screw shaft 13 during the swinging 10 movement.

An arcuate shutter 42 for closing the aperture 41 is confined between the guard plate and the front collar 33 of the sleeve and preferably rides on spaced lugs 43 at each 15 end of the slot 44 in the bed plate. The shutter is of less length than the guard plate and has an aperture 44 positioned at one side of its center to receive the screw shaft 13 and to be moved laterally thereby.

20 By virtue of the reduced length of the shutter it will not project beyond the guard plate when carried along with the screw shaft and yet it will close the aperture 41 throughout the stroke of the screw shaft 25 when the sash is being opened and the screw shaft is being laterally displaced in this operation.

In order that the shutter may be applied to a window opening on either a right or a 30 left handed pivot it is only necessary to rotate it 180 degrees about the screw shaft (Figs. 4 and 5). To permit of this reversing adjustment a slot 44 is provided in the bed plate 23 to allow passage of the small 35 end of the shutter. The adjustment may be quickly made without removing the screw shaft 13.

I claim:

40 1. An operating mechanism for a swinging member including a bed plate, a bearing member pivotally mounted at one end on the bed plate, a sleeve having an internally threaded collar at one end, said sleeve inserted in the bearing member and having the 45 collar abutting the bearing member, a separate collar on the opposite end of the sleeve and abutting the bearing member, means for securing the separate collar to the sleeve, means engageable with said preceding means 50 for rotating the sleeve, a screw shaft receivable in the sleeve and engaged with the threaded collar and means on the screw shaft engageable with the threaded collar to limit movement of the screw shaft.

55 2. An operating mechanism for a swinging member including a bed plate, a bearing member pivotally mounted at one end on the bed plate, a sleeve having an internally threaded collar at one end, said sleeve inserted in the bearing member and having the 60 collar abutting the bearing member, a separate collar on the opposite end of the sleeve and abutting the bearing member, means for securing the separate collar to the sleeve, means engageable with said preceding means 65

for rotating the sleeve, a screw shaft receivable in the sleeve and engaged with the threaded collar.

3. An operating mechanism for a swinging member including a support, a bearing member pivotally mounted at one end of the support, a sleeve having an internally threaded collar at one end, said sleeve inserted in the bearing member and having the collar abutting the bearing member, a 70 separate collar secured on the opposite end of the sleeve and abutting the bearing member, means for rotating the sleeve, and a screw shaft receivable in the sleeve and engaged with the threaded collar. 75

4. An operating mechanism for a swinging member including a support, a bearing member mounted on the support, a sleeve nut rotatable in the bearing member and abutting the ends thereof, a screw shaft receivable in the sleeve nut and means on the screw shaft cooperating with the sleeve nut 80 to limit movement of the screw shaft.

5. An operating mechanism for a swinging member including a bearing member, a 90 sleeve rotatable in the bearing member and having an internally threaded portion, a screw shaft receivable in the sleeve and engageable with the internally threaded portion thereof, and a screw secured axially to 95 one end of the screw shaft and engageable with the threaded portion of the sleeve to limit movement of the screw shaft.

6. In an operating mechanism, a bearing member including a flat bottom plate with 100 offset portions, an arched top plate having lugs securable to the bottom plate, a sleeve rotatable in the bearing member, collars on the sleeve abutting the ends of the arched top and bearing on the offset portions of the bottom plate, and a screw shaft receivable in the sleeve. 105

7. In an operating mechanism, a bearing member including a flat bottom plate and an arched top plate, a sleeve rotatable in the bearing member, collars on the sleeve abutting the ends of the arched top plate, and a screw shaft receivable in the sleeve. 110

8. In an operating mechanism, a support having a recess, a bed plate in the recess having a slot, an arcuate guard plate on the bed plate and extending across the recess in the support, said guard plate having an elongated aperture, a laterally swinging member extending through the aperture in the guard plate, a bearing for said swinging member, an arcuate shutter confined between the guard plate and the bearing and having an aperture off-center to receive the swinging member, lugs on the bed plate at each end of the slot and supporting the shutter, and said shutter reversible on the swinging member by having one of its ends move through the slot in the bed plate. 120

9. In an operating mechanism, a support 125

having a recess, a bed plate in the recess having a slot, an arcuate guard plate extending across the recess in the support, said guard plate having an elongated aperture, 5 a swinging member extending through the aperture in the guard plate, an arcuate shutter on one side of the guard plate, said shutter having an aperture off-center to receive the swinging member, and the shutter 10 being reversible on the swinging member by having one of its ends move through the slot in the bed plate.

10. In an operating mechanism, a support having a recess, a guard plate extending 15 across the recess in the support and having an elongated aperture, a swinging member extending through the aperture in the guard plate, a shutter for the elongated aperture in the guard plate, said shutter rotatably 20 mounted on the swinging member and reversible in place.

11. In an operating mechanism, a support having a recess, a guard plate extending across the recess in the support and having 25 an elongated aperture, a swinging member extending through the aperture in the guard plate, a shutter for the elongated aperture in the guard plate spaced supporting means normally maintaining the shutter in position to close the elongated aperture, said 30 shutter rotatably mounted on the swinging member and reversible thereon by having one of its ends move between the spaced supporting means.
